C. W. KIRSCH

WINDOW SHADE ROLLER FIXTURE

Filed Nov. 23, 1922

UNITED STATES PATENT OFFICE.

CHARLES W. KIRSCH, OF STURGIS, MICHIGAN.

WINDOW-SHADE-ROLLER FIXTURE.

Application filed November 23, 1922. Serial No. 602,905.

To all whom it may concern:

Be it known that I, CHARLES W. KIRSCH, a citizen of the United States, residing at Sturgis, in the county of St. Joseph and State of Michigan, have invented certain new and useful Improvements in Window-Shade-Roller Fixtures, of which the following is a specification.

This invention has for its object to provide a window-shade roller fixture including, as an integral part thereof, the brackets required to pivotally support a window-shade roller of the Hartshorn or similar type, and a companion element, also integral therewith, to which a hood for covering the extreme end portions of the shade roller may be detachably secured, and wherein the last-named element of the fixture, and the hood, are so associated when coupled, as to present to the eye no open space beyond the end of the shade roller.

The invention may be embodied in fixtures adapted to be mounted on the front surface of a window frame or the like or upon the opposed side walls thereof, both embodiments, in their preferred form, being illustrated in the accompanying drawings in which:

Figure 1 is a perspective view of a pair of fixtures constructed in accordance with my invention, together with a window shade roller and window shade supported thereby, showing the same mounted upon the front wall of a window casing;

Fig. 2 is a vertical transverse section on the line 2—2 of Fig. 1;

Fig. 3 is a horizontal or plan section on the line 3—3 of Fig. 1;

Fig. 4 is a detail perspective view of one member of the fixture;

Fig. 5 is a similar perspective view of the fixture as embodied to adapt it to be secured to one of the opposed side walls of a window casing or the like; and

Fig. 6 is a detail perspective view of the hood adapted to be associated with the respective fixtures shown in Figs. 4 and 5.

The present invention resides in certain improvements in the device illustrated and described in Letters Patent of the United States No. 1,388,346, dated August 23, 1921.

The main object of the present invention is, however, to provide means for so hiding the ends of a window shade roller from view, which are inseparably associated in part with the fixtures for rotatably sup-

porting the window-shade roller in the ordinary manner, whereby the relative positions of such fixtures and the cover means may be definitely maintained and both thereof simultaneously mounted on a window casing without the double work and measuring required where such fixtures are separate from each other.

A further object of the invention is to provide a window-shade fixture of the character set forth adapted for mounting either on the front face or the opposed side walls of a window casing or the like wherein the hood and the means for detachably securing the same to such fixtures are identical and interchangeable, that is to say, so that the same hood may be used for either type of such fixtures.

Referring now to said drawings and particularly to Fig. 4, thereof, it will be seen that the device comprises a plate 1 equipped on opposite parallel edges with parallel flanges 2 and 3, the latter being formed to adapt the same to receive the respective end projections of a window-shade roller, as for example, is shown in Fig. 4 for one end, and in Fig. 2 for the other end of such roller. The flange 2 terminates at its extreme end in a tongue 4 equipped with an integral flat spring portion 5 at about its middle, said tongue being adapted to engage formations of the hood 6, hereinafter described, for detachably securing said hood to said flange.

The plate 1 is further provided along one edge, with projections 7 having openings or perforations 8 therein for the passage of screws, or the like, by means of which said plate may be secured to the front face of a window casing. In Fig. 4 the said projections 7 are disposed contiguous to the side edges of the flange 3 and are flush with the middle portion of the plate 1, whereas, as shown in Fig. 5, said projections are disposed contiguous to the opposite side edges of the flange 9 (corresponding generally with the flange 2 of Fig. 4) and extend perpendicularly or substantially perpendicularly to the middle portion of the plate 10, (corresponding to the plate 1 of Fig. 4) said plate 10 being, however, slightly curved and terminating in the shade-roller fixture or bracket 11 corresponding to the fixture or bracket 3, shown in Fig. 4.

The extreme end portion 12 of the flange 9 corresponds in size and shape and in every other detail, with the tongue 4 of Fig. 4, so

that the same hood 6 adapted to be mounted upon said tongue 4, may be also interchangeably mounted upon the said end portion 12 of the flange 9.

5 Referring now to Fig. 6, it will be noted that the hood consists of the substantially semi-cylindrical wall portion 6, the ends of which terminate in parallel flat flanges 13. Said hood is provided with an end wall 14, 10 out of which there are struck a plurality of pairs of opposed L-shaped projections or flanges 15 between the outermost portions of which, and the inner face of said wall 14, the tongue 4, or end portion 12 of the flanges 15 2 or 9, respectively, are adapted to be received and engaged, the side edge portions of said tongue 4, and end portion 12, respectively, being adapted to abut against the lugs of said flanges or projections 15, in an 20 obvious manner. The springs 5 are offset out of register with the opposite faces of the tongue 4 and end portion 12, respectively, and outwardly with respect to the outer face thereof and are adapted to bear upon 25 the inner face of the end wall 14 of the hood to provide sufficient frictional engagement to firmly hold the hood engaged with the tongue or end portion, respectively, referred to.

The said end-wall 14 of the hood is provided with a recess 16 midway between its side edges, said recess being of slightly greater width than the tongue 4 or end portion 12 and being adapted to have the inner face of its end wall become disposed flush 35 and in contact with the base of the tongue 4 or end portion 12, the portions of the end wall bordering the sides of the recess 16 being adapted, in the case of the fixture shown in Fig. 4, to overlap that portion of the flange 2 which is disposed inwardly of the tongue 4. The portion referred to may be said to extend from the plane of the shoulders 17 outwardly to the base of the tongue 4, thus providing recesses or cut away portions 45 outwardly of the base portion of the flange 2 into which the flanges 13 are adapted to project. Thus, when the hood is mounted on the fixture shown in Fig. 4, there will be no open space between the base of the flange 2 and the outermost portion of the hood 6, 50 this being particularly illustrated in Fig. 2.

Owing to the fact that the projections 11, in the case of the construction shown in Fig. 5, must be cut out of a part of the 55 metal which, in Fig. 4, constitutes the flange 2, the end portion 12, corresponding to the

tongue 4, is of slightly greater width than the flange 9 inwardly thereof, so that when the hood is mounted on said portion 12, the portions of the end wall at the sides of the recess 16, will overlap the projections 11 and, because of the fact that said projections are secured to a side wall of a window casing or the like, such overlapping effects substantially the same results, in so far as presenting no open spaces to the eye is concerned, as the overlapping of a portion of the flange 2 by the said portion of the end wall bordering the slots of the recess 16, accomplishes with respect to the structure 70 shown in Fig. 4.

Obviously the invention may be somewhat differently embodied from the exact details of construction shown in the accompanying drawings without departing from the invention as defined in the appended claims.

I claim as my invention:

1. A shade roller fixture comprising a plate, a pair of perforated projections integral therewith and disposed at opposite end portions thereof whereby the plate is adapted to be rigidly secured to a window casing, a flange extending from the same edge of said plate as said projections and midway between the latter, the free end portion of said flange provided with means for engaging a pivot element of a shade roller, a second flange extending from the opposite edge of said plate parallel with the first named flange, a hood adapted to cover and hide from view the first named flange and the contiguous portion of a shade-roller engaged therewith, and inter-engaging formations on said last named flange and said hood for separably coupling them. 95

2. In a device of the kind specified as defined in the preceding claim, including a substantially semi-cylindrical hood having one end wall and having its semi-cylindrical wall terminating in parallel flanges separated from each other a distance substantially equal to the width of the plate, the end wall of said hood extending between said flanges and presenting an edge flush with the ends thereof, the said end wall of the hood adapted to overlap a parallel portion of the structure when disposed in normal position thereon whereby to obviate open spaces between the innermost edge portion of the end wall of the hood and the 100 plate. 105

CHARLES W. KIRSCH.
